UNITED STATES PATENT OFFICE.

JOHN P. HAYES, OF PHILADELPHIA, PENNSYLVANIA.

PLUMBER'S BLAST-FURNACE.

SPECIFICATION forming part of Letters Patent No. 537,573, dated April 16, 1895.

Application filed March 28, 1894. Serial No. 505,375. (No model.)

To all whom it may concern:

Be it known that I, JOHN P. HAYES, a citizen of the United States, residing at the city of Philadelphia, in the county of Philadelphia and State of Pennsylvania, have invented certain new and useful Improvements in Plumbers' Blast-Furnaces, of which the following is a specification.

My invention has relation to a portable furnace or heating apparatus for plumbers' and other somewhat similar uses; and it relates more particularly to the general construction and arrangement of the parts thereof so as to be especially adapted for the vaporizing and burning as fuel of high grade or fire test oils therein for heating purposes.

Hitherto high grade or fire test oils have not with any degree of success been vaporized and burned in such type of furnaces for constituting a fuel thereof, but on the contrary gasoline or the like has been almost universally used in such furnaces with its attended danger of explosion unless due care was exercised in the employment thereof.

The principal objects of my invention are, first, to provide a simple, durable and effective portable furnace especially adapted, owing to its construction and the arrangement of the parts thereof, for expeditiously and thoroughly vaporizing and burning high grade or fire test oils therein for obtaining excellent calorific power therefrom; second, to provide a plumber's blast furnace in which the oil in transit is thoroughly vaporized in advance of combustion in order that increased heat imparting properties may be derived from the superior quality of the gas economically generated therein for use in the furnace in reducing matter to a molten or liquid state; third, to provide a plumber's blast furnace with a heating coil and with a needle jet valve in communication therewith and provided with a non-consumable body located adjacent thereto and adapted to constitute by the saturation of the same with oil a firing bed for hastening vaporization in the transit of the oil under pressure from the reservoir upon starting of the furnace; fourth, to provide a portable blast furnace with a reservoir having suitable pipe connections merging into a coil and with a non-consumable firing bed located adjacent to a needle valve adapted to permit of the expeditious and complete combustion of the gas generated from the oil in

transit upon application of a flame thereto 55 and of continuous heating for effecting thorough vaporization of the oil in its transit from the reservoir of the furnace in the use thereof, whereby a gas of high calorific power is obtained and far better heating properties 60 derived therefrom, and, fifth, to provide a portable blast furnace with a detachable inversely tapering flame concentrator pot and with a heating and vaporizing coil having a needle operated valve adapted to control the 65 character of the combustion of the gas from the oil in transit and increased calorific power in application of the furnace.

My invention stated in general terms consists of a portable blast furnace constructed, 70 arranged and adapted for operation in substantially the manner hereinafter described and claimed.

The nature and scope of my invention will be more fully understood from the following 75 description taken in connection with the accompanying drawings forming part hereof, and in which—

Figure 1, is a side elevational view of a plumber's blast furnace, embodying features 80 of my invention. Fig. 2, is a top or plan view of an apertured support for the flame concentrator pot, and showing also the arrangement of the coil with a needle operating valve for controlling the exit of oil and of the gas generated from the oil for effecting ignition in the one instance and in the other the combustion thereof. Fig. 3, is a perspective view of the apertured holder or support and a central broken section of the flame concentrator 85 pot of Fig. 1, showing the manner of clamping the same to position in connection with the holder or support of the furnace. Fig. 4, is a view partly in elevation and partly in central section of the furnace of Fig. 1. Fig. 90 5, is a similar view, showing the detail construction of the needle operating valve and its location in the tapering perforated air and gas mixing chamber. Fig. 6, is a top or plan view of the heating and vaporizing coil, 100 top of the air and gas mixing chamber and T-union with its detachable grooved plug for controlling the flow of the fluid to the heating and vaporizing coil connected with said union and permitting of the cleaning of the same by 105 the removal thereof from said union. Fig. 7, represents a perspective view of the detachable grooved and threaded plug-valve with

its flanged integral nut for engaging the T-union and permitting by means of a wrench of the turning of the same in said T-union of the type illustrated in Figs. 1, 2, 4, 5, and 6. Fig. 8, is a view partly in elevation and partly in central section of one of the ears of the holder with its tapering end stud and its complementary looped bearing of the bail; and Fig. 9, is a perspective view of said parts of the holder and bail, showing the position of the looped bearing of the bail with one of the tapering end studs of an ear of the holder in engagement therewith in an operative position of the bail.

15 Referring to the drawings A, is a reservoir provided with rods or posts a , a' and a'' , having both ends threaded and adapted to detachably engage complementary threaded openings provided in the top of the reservoir and lugs b , b' and b'' , of an apertured holder B, having preferably integral ears b^3 and b^4 , with tapering end studs b^5 and b^6 , engaging complementary loop bearings c , on each side of a bail C, with a handle C'. The end studs b^5 and b^6 , are arranged so that the bearings c , of the bail C, may be readily caused to engage the contracted portions of these bearings when the bail has assumed a vertical position with respect to the furnace, whereby 30 the same in such position will support the furnace so that it can be safely carried from place to place in an upright condition.

The support B, is provided with integral recessed clamps b^7 , extending from the central aperture b^8 , thereof outwardly toward the periphery so as to permit of the engagement therewith of the base of an inversely tapering flame concentrator pot D. The base d , of this pot, has inwardly flanged recesses d' , 35 d^2 and d^3 , and a series of lugs d^4 , projecting also inwardly and on each side of the series of recesses of the base, in order that by a slight rotary movement of the pot D, by hand or otherwise, the same may be brought into engagement with the series of clamps b^7 , of the holder B, for supporting the pot D, to required position.

The construction of the pot D, is such that the flame rising from the combustion of the 50 vaporized oil through the perforated air and gas mixing chamber E, which is supported by means of screw bolts or rods e , e' and e'' , from the holder B, will take the freest line of travel in an upward direction along the inner surface of the inversely disposed tapering pot D, thereby imparting its heat to the solder or other matter to be melted in a receptacle resting on the series of clamps b^7 , formed integral with the holder B.

55 a^4 , is a threaded opening formed in the top of the reservoir A, and provided with a screw plug a^5 , having an eye a^6 , preferably formed integral therewith and adapted for the reception of a rod or the like for readily releasing this plug from its seat in the opening a^4 , in order to permit of the introduction of the fire test or high grade oil into the reservoir A.

a^7 , is a curved tube screwed into the top of the reservoir A, and provided with a stopcock a^8 . This tube is provided with a contracted exit or nozzle for the application of flexible or rubber tubing thereto with a bulb or the like, not shown, for forcing air into the interior of the reservoir in order to lift the oil through the detachable pipe a^9 , screwed into the top of the reservoir and engaging a T-union a^{10} , with a plug valve a^{11} , so arranged in connection therewith as to retard the flow of oil in its transit under pressure through the pipe a^9 and T-union a^{10} , to the coil a^{12} , 75 screwed into the said T-union a^{10} , for example, as illustrated in Figs. 6 and 7. This partially threaded plug valve a^{11} , has a longitudinal groove a^{13} , formed in the body thereof to constitute a narrow channel for the oil to flow therethrough and this valve is provided with an integral flanged hexagonal or other shaped nut a^{14} , for the reception of a wrench or like tool to retard or stop the flow of oil from the reservoir A, through the pipe a^9 , to the coil a^{12} . This coil a^{12} , extends in a downward direction through the perforated air and gas mixing chamber E, and terminates in a valve coupling F, with internal channels f and f' , and with a bonnet or casing f^2 , having an internal chamber f^3 , which may be employed as a storage chamber for the generated gas or may be provided with a packing of asbestos or other preferred material to prevent leakage of the oil from the device F. It should be 90 borne in mind that this material must be of such character as to permit of the free movement of the needle valve f^4 , as requirements demand.

The bonnet or casing f^2 , is detachably secured to the coupling F, as fully illustrated in Fig. 5, and the partially threaded needle valve stem f^{10} , has a regulating nut, cap or handle f^5 , with preferably openings therein for the introduction of a rod f^7 , in order to control the position of the needle valve in the coupling F, and regulate the flow of oil in the one instance through the interior to the non-consumable bed of asbestos or other preferred material and in the other instance of a 115 jet flame issuing from the needle cock f^4 , into surface contact with the coil a^{12} , for vaporizing the oil in its transit therethrough from the point of connection of the coil with the T-union a^{10} , and thus to increase the degree 120 of vaporization and to enhance the combustion as well as calorific power of the gas issuing therefrom, for heating the furnace.

The bed of non-consumable material f^8 , is mounted in a casing f^9 , located adjacent to the coupling F, and is supported to required position in engagement with the bonnet or casing f^2 , of the device F. I do not wish, however, to limit myself to the precise position of the bed f^8 , as illustrated in the drawings.

130 It may be here remarked that the construction and arrangement of the valve and its coupling and the parts connected therewith are such, that by the application of a match

or lighted taper to the supported bed of non-consumable material mounted in the casing located adjacent to the needle valve, an intense flame can be readily derived therefrom for creating a thorough vaporization of the oil in its transit through the coil a^{12} , to permit of the expeditious heating of matter to be reduced to a molten or liquid condition in the path of the flame derived therefrom. The apertures provided in the chamber E, are for enhancing combustion and also concentrating the flame in the direction of the coil a^{12} , in order to insure an intense flame being derived therefrom through the uniform spreading of the same so as to envelop the exposed surfaces of the coil and thus to thoroughly vaporize the oil in transit through the coil to the needle valve f^4 , and give a resultant gas of high calorific power for heating purposes.

The operation of the apparatus hereinbefore described, is as follows: The reservoir A, is filled with oil through the opening a^4 , by the removal of the plug a^5 , and when a^5 placed the stop-cock a^8 , in the curved tube a^7 , is then opened and a rubber tubing with a pump or bulb, is applied to the nozzle of said tube a^7 , and manipulated so as to force air into the interior to lift the oil, after the needle cock valve f^4 , has been adjusted by means of the rod f^7 , through the pipe a^9 , T-union a^{10} , coil a^{12} , and channels f and f' , of the bowl-shaped coupling F, onto the bed of non-consumable absorbent material f^8 . A match may then be applied to the bed f^8 , which will at once produce a flame of considerable intensity for starting the furnace and vaporization of the oil in transit and by means of the air drafts or apertures in the air and gas mixing chamber E, the flame from the combustion of the oil gas will be directed toward the surfaces of the coil a^{12} , thereby thoroughly vaporizing the oil passing through the same and when the oil saturated bed f^8 , has been consumed by the burning off of the same, the flame will have produced a sufficient vaporization of the oil in transit through the coil to ignite the gas issuing at the exposed upper end of the needle cock f^4 , and which flame derived therefrom will be concentrated in the direction of the surfaces of the coil a^{12} , and the heat arising from the same will follow an upward course along the wall of the pot D, and as well the flame will lick against the body of matter to be melted in a solder pot held on the holder B, thereby expeditiously reducing the same to a liquid or molten state, for use.

It may be here remarked that in such type of blast furnace it is essentially requisite that the flame directed from the furnace should quickly reduce the matter to a molten condition and the conditions are present in the form of furnace such as hereinbefore described to effect such a result in the shortest possible time, with the greatest economy in the quantity of gaseous fuel consumed and

with the waste of oil in the production of the gas for such purpose reduced to a minimum.

In practice with the T-union a^{10} , having a detachable grooved plug-valve a^{11} , for example, as illustrated in Figs. 6 and 7, a retarding influence is presented to the free flow of the oil under pressure in an upward direction through the pipe a^9 , from the reservoir A, to the coil a^{12} , and such a valve is readily removable from the T-union a^{10} , to permit of cleaning of the same when becoming clogged by the accumulation of extraneous matter carried thereto with the oil.

Having thus described the nature and objects of my invention, what I claim as new, and desire to secure by Letters Patent, is—

1. A plumber's blast furnace provided with a heating and vaporizing coil, a bowl-shaped casting provided with internal channels, an oil cup connected with said casting so as to form an annular channel around the same and the edge of said cup being on a level with the top of said casting, a needle cock in said casting, and means for actuating the same, substantially as and for the purposes described.

2. A plumber's blast furnace provided with a holder having tapering ears on both sides thereof and a bail having an angular part to correspond to each of said ears and said part merging into a circular opening of said bail to permit of a turning movement of the latter in connection with each of said ears of the holder, substantially as and for the purposes described.

3. A plumber's blast furnace provided with a heating and vaporizing coil, a bowl-shaped casting having internal channels and a needle-cock, an oil cup arranged to form an annular channel between said casting and cup and the upper edge of said cup on a level with the top of said casting, substantially as and for the purposes described.

4. A plumber's blast furnace provided with a fluid supply, a T-union connected therewith, a cylindrical bar removably mounted in said union and provided with an oblong groove formed in the body thereof and one portion of said bar threaded and having a collar or shoulder and a nut, substantially as and for the purposes set forth.

5. A plumber's blast furnace provided with a reservoir having an oil supply in connection with a heating and vaporizing coiled retort, a bowl-shaped casting having internal channels in connection with said retort, a needle-cock in said casting an oil cup arranged to form an annular channel between said casting and cup and the upper edge of said cup being on a level with the top of said casting, substantially as and for the purposes described.

In testimony whereof I have hereunto set my signature in the presence of two subscribing witnesses.

JOHN P. HAYES.
